UNITED STATES PATENT OFFICE.

ROBERT ABSALOM THOM, OF BEARDSDEN, NEAR GLASGOW, AND JAMES THOM, OF ABERDEEN, SCOTLAND, ASSIGNORS TO THE SUPERHEATER COMPANY, OF NEW YORK, N. Y.

STEAM GENERATOR.

Application filed June 11, 1926; Serial No. 115,296, and in Great Britain June 9, 1925.

This invention relates to improvements in steam generators of the type having water tube fire-boxes, such for instance as the steam generator shown and described in the specification of our co-pending application Serial No. 680,510, and has for its principal object to provide a construction of steam generator of the type indicated in which the usual fire-box stays at the back plate or fire-door end 10 of the fire-box may be eliminated. It is a further object of the invention to enable the back plate water space of the fire-box to be employed as a feed water heater.

In certain water tube fire-box constructions, including that according to the specification of said prior patent, water distributors and a water or steam collector or receiver are associated with down-flow and up-flow water tubes, constituting the side walls 20 of the fire-box or furnace chamber, and with the water and steam spaces of the boiler.

It is well known that fire-box stays are a source of trouble in steam boiler practice and in the prior constructions having water tube side walls to the fire-box, as for instance in our prior patent above referred to, the usual side and crown stays are eliminated. As above indicated, by means of the present invention the usual back plate water space stays may also be entirely or almost entirely eliminated.

The present invention principally consists in a steam generator of the type having a water tube fire-box, wherein the back plate water space of the fire-box is so constructed and associated with other parts of the steam generator and its equipment that the said space constitutes a feed water heater.

A steam generator according to this invention comprises appropriately disposed water distributors and a water or steam receiver or receivers associated with water heating and steam generating tubes at the sides of the furnace, the said distributors and receiver or receivers being in open communication at their forward ends with the body or barrel of the boiler, and having their rear ends secured to the back plate of the boiler and closed by removable cover plates, means being provided to protect said back plate from the direct action of the furnace gases. The means for protecting the said back plate may be a water space not under boiler pressure and constituting the

above mentioned feed water heater, or the back plate may be protected by refractory and heat insulating means.

The invention further consists in the construction, combination and arrangement of parts pointed out in the appended claims and particularly described hereinafter with reference to the accompanying drawings, in which,—

Fig. 1 is an elevation, more or less diagrammatical, of the back plate of a locomotive boiler according to this invention, showing also a feed pump hereinafter referred to, and

Fig. 2 is a central longitudinal section through the fire box of a locomotive boiler embodying this invention, having a back plate arrangement as shown in Fig. 1, the section being taken on the line A—B of Fig. 1 and looking in the direction of the arrow.

Referring to the drawings, 1, 1 are the water distributors and 2 is the steam or steam and water receiver or collector, 3 and 4 being the down-flow and up-flow water tubes respectively at the sides of the fire-box secured at their upper ends to and communicating with the distributors 1 and receiver 2 and at their lower ends to and communicating with headers 5 as in the prior specification above referred to. Preferably the pipes 3 and 4 are formed into pairs, the pipes of a pair being united at their ends to, or forged to form, a single portion as shown for connection to the distributor, collector or header as the case may be, 6 is the boiler barrel, 7 the smoke tubes, 8 the front plate of the fire-box and 9 the back plate thereof, the distributors 1 and collector 2 being in open communication at their forward ends with the boiler barrel as in the earlier specification referred to.

According to this invention the ends of the water distributors 1 and collector 2 at the back-plate end of the fire-box are closed by removable covers 1^a 2^a, access thus being obtainable for expanding the tubes into the distributors and collector and for cleaning, and the distributors and collector may be suitably secured, for instance directly as shown, to the back-plate 9, as by bolts or equivalent means passing through a flange 10 or 10^a, preferably inturned, at the end of such distributor or collector and through the back plate 9. Such flanges 10, 10^a may conven-

iently be provided by welding or otherwise securing to the appropriate end portion of each of the distributors and the collector, respectively, an angle ring, the outer periphery of which ring is preferably welded to the inner periphery of the distributor or collector.

To protect the back plate from the direct action of the flame and hot furnace gases 10 refractory and heat insulating means may be employed, or a water space 11 not under the boiler pressure may be employed, and in the latter case the feed water may pass or be passed through the said space 11 from 15 the water tank or tender on its way to the water space of the boiler via the main feed pump or injector (not shown).

In the case of refractory material being employed to protect the back plate, such 20 material may consist of suitably supported fire bricks or slabs and between such bricks or slabs and the back plate one or more sheets of asbestos or other suitable heat insulating material may be placed, such asbestos or 25 other sheeting being preferably strengthened by wire gauze insertions and being secured to the back plate by bolts, preferably galvanized, having their heads sunk in such sheeting. The front plate 8 may be similarly 30 protected by refractory material as shown in Fig. 2, 12 being fire bricks or slabs, and 13 asbestos or equivalent sheeting interposed between the fire brick and the plate 8.

As above mentioned the back plate 9 may 35 be protected by a water chamber 11 not under pressure, which may be employed as a feed water heater, and it is this embodiment 40 of the invention which is shown in the drawings. The space 11 between the inner back plate 14 and outer back plate 9, the former constituting the rear plate of the furnace chamber, is provided near its lower end with 45 a connection 15 to the water tank or feed water supply. The connection 15 leads directly to such tank or supply for use in feeding the back plate water space 11 by gravity or by the natural flow of the water to destroy the vacuum created by the suction of the boiler feed pump or ejector from the said 50 water space, which natural flow will take place as long as the temperature of the water in the said space does not rise to too high a degree. Another connection 16 is provided leading from the discharge outlet of a suitable 55 pump 17 for use in feeding the space 11 from the supply tank should the level of water not be maintained by gravity or natural flow feed. Non-return valves 18, 19 are provided in the connections 15, 16 and 60 the intake of the pump 17 is connected to a pipe 20 leading from the feed water supply. At a suitable height a connection 21 is taken from the back plate water space or feed water heater 11 to the intake of the main feed pump of injector, capable of handling 65

hot feed water, and the steam supplies for both the latter pump or injector and the pump 17 may conveniently be taken from the steam and water collector or receiver 2 by valve controlled pipes 22, 23 secured to 70 the back plate 9 in registration with holes leading therethrough into said collector or receiver 2. The exhaust steam from the pump 17 may be carried by a pipe 24 to a condensing coil in the feed water tank of 75 the engine or tender the outlet from which coil would be above the high water level in said tank and may be down-turned. In order to prevent the pressure in the back plate water space 11 rising above a predetermined degree, say 7 lbs. per square inch, a loaded valve 26 may be provided in a pipe 27 leading back to the water tank of the engine or tender and this pipe may terminate 80 in the tank in a cooling or condensing coil 85 similarly to the pipe 24.

The pump 17 may be, and preferably is, equipped with an automatic governor adapted to set the pump in action whenever the water in the space 11 falls below a predetermined level. Should the pressure rise above the predetermined degree due to steam being generated in the feed water heating space 11 the valve 26 will open and heated water will flow back to the supply tank through 90 the pipe 27. The water level in the space 11 will thus fall and the pump 17 will come into operation thus replacing the hot water returned to the tank with cooler water from 95 said tank and thus lowering the temperature 100 in the space 11 and consequently the pressure therein.

In order to enable the back plate water space 11 constituting, according to this embodiment of the invention, a feed water heater to be cleaned when necessary or desirable, a suitable number of wash-out plugs 28 would be provided, such plugs being appropriately located in the back plate, one or more being close to the bottom of the water 110 space and one or more in the upper portion of the back plate. Further, there is preferably provided one or more hand holes in the back plate, closed by suitable covers 29, to enable scrapers to be inserted and manipulated should such be found necessary in order to dislodge or remove incrustation 115 from the surfaces of the parts in contact with the water.

The water distributors 1, 1, and the steam and water collector 2, in addition to being secured to the outer back plate 9, are secured to the inner back plate 14 where they pass through such plate and thus act to stay these plates 9 and 14, the fire-hole throat ring, if employed, being also secured to both plates and acting as a further staying means. Alternatively the inner and outer back plates may be pressed to shape as shown and secured together at the fire-hole 30. 120 125 130

As above mentioned, the construction according to the present invention is such that the usual fire-box stays in the back water space 11 may be eliminated, owing to the absence of any substantial pressure in said space. It is, however, considered preferable to provide a few stays 31 between the plates 9 and 14, as indicated in Fig. 1.

If desired, in order to prevent the water 10 in the back plate space 11 being heated to an undesirably high degree, the inner back plate 14 may be protected by heat insulating and refractory materials, such for instance as by asbestos sheeting arranged between the 15 said plate 14 and suitable fire bricks or slabs.

Variations may be made in details of construction without departing from the invention.

Having now particularly described and 20 ascertained the nature of our said invention and in what manner the same is to be performed, we declare that what we claim is:

1. In a boiler of the locomotive type, a fire box having a plurality of water cooled 25 walls, one of said walls forming a water space independent of the water spaces of the remaining walls, a conduit supplying boiler feed water to said independent water space, and a connection leading from said 30 independent water space to the boiler.

2. In a boiler of the locomotive type, a fire box having a rear wall forming a water space independent of the boiler, a conduit supplying boiler feed water to said rear wall 35 and a connection leading from the rear wall water space to the boiler.

3. In a boiler of the locomotive type, a fire box having a rear wall forming a water space independent of the boiler, means for 40 supplying boiler feed water to said rear wall, a connection leading from the rear wall water space to the boiler, and a pump in 45 said connection whereby said rear wall may be operated at a pressure below that in the boiler.

4. In a boiler of the locomotive type, a fire box having side walls comprising a plurality of steam generating tubes forming a part of the boiler and a rear wall forming a water space independent of the boiler, a 50 conduit supplying boiler feed water to said rear wall, and a connection leading from the rear wall water space to the boiler.

5. In a boiler of the locomotive type, a plurality of water cooled walls, one of which 55 forms a feed water heater for said boiler, a conduit delivering feed water to said heater by gravity, an auxiliary pump for forcing feed water thru said heater, and a discharge conduit leading from the heater to the boil- 60 er feed pump.

6. In a boiler of the locomotive type, a fire box having side walls comprising a plurality of steam generating tubes forming 65 part of the boiler, and a rear wall comprising a pair of spaced sheets defining a water space separate from the boiler, means for supplying boiler feed water to said rear wall water space, a connection leading from said rear wall water space to the boiler, and a 70 pump in said connection whereby said rear wall may be operated at a pressure below that in the boiler.

7. A locomotive boiler fire box comprising a longitudinal steam and water drum, 75 a pair of spaced headers located below said drum, steam generating tubes connecting said drum with each of said headers and defining the side walls of said fire box, a pair of spaced sheets closing the space between said drum and headers at one end thereof to form the rear wall of said fire box, said sheets defining a water space separate from the boiler, means for supplying boiler feed water to said rear wall water 80 space, and a connection leading from said rear wall water space to the boiler.
